UNITED STATES PATENT OFFICE

2,469,548

CHILD'S SEAT FOR BARBER CHAIRS

Emmett L. Connelly, El Monte, Calif.

Application March 8, 1946, Serial No. 653,036

3 Claims. (Cl. 155—131)

1

This invention relates to a child's seat for barbers' chairs.

It has been a customary practice for many barbers to attempt to keep available a suitable board that may be positioned on a barber's chair so as to bridge the arms of the chair to provide an elevated seat for children. Such a board when applied supports the child at a desired elevation which cannot ordinarily be obtained with the conventional barber chair. When adult customers are seated in the chair the board is removed but when wanted the board is frequently kept at a remote location and sometimes cannot be readily found.

An object of the invention is to provide an improved child's seat for barbers' chairs consisting of an upholstered board or bridging member adapted to bridge the arms of the barber chair and having a bracket hingedly connected thereto adapted to be more or less permanently attached to the chair enabling the board or bridging member to be swung into a position bridging the arms or assume a position hanging from adjacent one arm downwardly so as to be readily available.

More specifically, an object of the invention is to provide a child's seat for barbers' chairs having a bracket hingedly connected thereto which is so designed as to be applicable to one of the bolts attaching the arm of the chair to its back so that the bracket may be applied to the conventional barber chair without marring its appearance or requiring alteration of the chair.

With the foregoing and other objects in view, which will be made manifest in the following detailed description and specifically pointed out in the appended claims, reference is had to the accompanying drawings for an illustrative embodiment of the invention, wherein:

Figure 1 is a perspective view of a barber's chair illustrating the improved child's seat in applied position thereon;

Fig. 2 is a top plan view of the seat;

Fig. 3 is a view in front elevation of the same; and

Fig. 4 is a view in end elevation of the same.

Referring to the accompanying drawings wherein similar reference characters designate similar parts throughout, 10 indicates generally a conventional barber's chair consisting of a seat 11, a back 12, and arms 13 and 14. The arms are pivotally supported at 15 and are pivotally secured such as by bolts 16 to the back of the chair to enable the chair to assume a reclining position.

The improved child's seat consisting of a board

or the equivalent indicated at 17 may be upholstered as indicated at 18 and which is of such a length as to bridge the arms 13 and 14. To one end edge of the board there is attached a bracket consisting of a substantially horizontal rod 19 having its ends 20 and 21 bent downwardly and then inwardly as indicated at 22 and 23. The extreme end of the portion 22 is bent downwardly and is bifurcated as indicated at 24 so as to be receivable over the bolt 16 that attaches the arm 14 to the back 12. The portion 23 terminates in an inwardly extending eye 25 adapted to be positioned against the underside of the arm 14 forwardly of the bolt 16 and adapted to have a screw or other fastening device driven therethrough into the underside of the arm.

The hinge connection between the board and the bar 19 is provided by a pair of knuckles 26 and 27 secured to the underside of the board and surrounding the bar. One of these knuckles may be divided such as that indicated at 27 to accommodate a collar 28 secured to the bar to prevent longitudinal sliding of the board with respect to the bracket. The upright portions 20 and 21 of the bracket are of such a length as to position the horizontal portion 19 approximately even with the top of the arm 14 and outwardly of the arm. The upright portion 21 preferably has incorporated therein a threaded joint 22 so that its effective length may be varied or adjusted to properly position the horizontal portion 19 with respect to the arm by screwing or unscrewing the joint. The bifurcated end 24 permits of some slight adjustment of the portion 20 with respect to the bolt 16. On the opposite end of the board there may be applied rubber bumpers 29 which are engageable with the top surface of the arm 13. In use the board assumes a position bridging the arms 13 and 14 to support a child thereon at the desired elevation. However, when adult customers are using the chair the board may be swung into the dotted line position shown in Fig. 1, wherein it is suspended from the side of the arm 13 so as to be readily available whenever occasion requires.

It will be observed from the above-described construction that the device is readily applicable to a conventional barber's chair in that it is merely necessary in applying the device to loosen or back off the bolt 16 a sufficient distance to accommodate the bifurcated portion 24 and to drive a single screw or like fastener through the eye 25 into the bottom of the arm. In this way the child's seat may be applied to the chair with-

out marring its appearance or requiring any alteration in the construction of the chair.

It is to be observed that the presence of the child's seat on the chair does not interfere with the chair assuming an inclined position and that in mounting the seat on the chair the preferred position is that which is on the arm that is remote from the handle that controls the elevating mechanism of the chair so as not to interfere with movements of this end.

Various changes may be made in the details of construction without departing from the spirit and scope of the invention as defined by the appended claims.

I claim:

1. A child's seat for barbers' chairs comprising a board adapted to bridge the arms of a barber's chair, and a bracket hingedly secured to said board, said bracket consisting of a rod extending along one end edge of the board having its ends bent downwardly and then inwardly, one of said ends terminating in a downwardly bent bifurcated portion receivable over the bolt that pivotally attaches one arm of the chair to its back and the other inwardly bent end terminating in an eye through which a fastener may be driven into the underside of the arm of the chair.

2. A child's seat for barbers' chairs comprising a board adapted to bridge the arms of a barber's chair, a bracket hingedly secured to said board, said bracket consisting of a rod extending along one end edge of the board having its ends bent downwardly and then inwardly, one of said ends

terminating in a downwardly bent bifurcated portion receivable over the bolt that pivotally attaches one arm of the chair to its back and the other inwardly bent end terminating in an eye through which a fastener may be driven into the underside of the arm of the chair, and means for preventing longitudinal sliding movement of the board relatively to the bracket.

3. A child's seat for barbers' chairs comprising a board adapted to bridge the arms of a barber's chair and a bracket hingedly secured to one end of said board, said bracket having an arm extending downwardly from said end and then inwardly terminating at its inner end in a downwardly bent bifurcated portion receivable over the bolt that pivotally attaches one arm of the chair to the back of the chair, said bracket also having a portion extending downwardly and then inwardly terminating in a horizontal eye through which a fastener may be driven into the under side of the arm of the chair.
